CONTAINER

Hans A. Eggerss, Van Wert, Ohio

Application July 5, 1938, Serial No. 217,355

5 Claims. (Cl. 220—61)

My invention relates to containers. It has to do, more particularly, with a retaining or clamping ring adapted to be applied to the end of a cylindrical container in order to retain a removable head or closure in position at the end of the container.

This invention is particularly applicable to containers of the general type disclosed in my co-pending application Serial No. 158,768, filed August 12, 1937, although it is not necessarily limited thereto. The container disclosed in said co-pending application embodies a cylindrical body portion having a metal head for closing the end thereof, a retaining and clamping ring being provided for retaining the head in position. This invention specifically relates to the retaining and clamping ring. Although the retaining and clamping ring disclosed in said application has a number of desirable features, the retaining ring constituting this invention has a number of additional advantages.

One of the objects of my invention is to provide a retaining and clamping ring of the type indicated which is of such a nature that it may be readily applied to the container and will securely hold the head in position and may be readily removed in order to permit removal of the head.

Another object of my invention is to provide a retaining and clamping ring of the type indicated which is of such a nature that it may be used over and over again since it is so constructed that it will not be injured during its application to the container, during its use on the container or during its removal from the container.

Another object of my invention is to provide a retaining and clamping ring of the type indicated which is split to facilitate application to the container and removal therefrom, novel securing and locking means being provided for securing and locking the adjacent ends of the ring together.

Another object of my invention is to provide a split retaining and clamping ring of the type indicated wherein the securing and locking means is of such a nature that there will be no projecting or exposed portions which will be subject to injury or which will injure a person handling the container.

The preferred embodiment of my invention is illustrated in the accompanying drawing wherein similar characters of reference designate corresponding parts and wherein:

Figure 1 is a perspective view showing the adjacent ends of the retaining ring which are adapted to be superimposed.

Figure 2 is a similar view showing the adjacent

ends of the ring in overlapping cooperative relationship and showing how a locking pin may be applied in order to retain the ends of the ring in overlapping relationship.

Figure 3 is a horizontal section through the overlapping ends of the ring showing the locking pin being positioned therein.

Figure 4 is a similar view illustrating the structure after the locking pin has been positioned therein.

Figure 5 is a front elevation of the structure illustrated in Figure 4.

Figure 6 is a rear elevation of such structure.

Figure 7 is a vertical section taken through the upper end of a container illustrating how my retaining ring will hold the head in position and also showing a transverse section through the overlapping portions of the ring taken substantially along line 7—7 of Figure 5.

Figure 8 is a view similar to Figure 1 but showing a modification of my invention.

As previously indicated, my retaining and clamping ring is particularly applicable to a container and head structure of the type illustrated in my co-pending application Serial No. 158,768. As illustrated in Figure 7, the container structure comprises a body portion 1 which is preferably of cylindrical form. This body portion is preferably made of fibre board, pulp board, paper or straw-board, although it may be made of other material.

A head 2 is applied to the end of the container. This head may be of the structure disclosed in said co-pending application and is made of metal although it may be made of other materials. A reinforcing metal band 3 embraces the upper end of the container and is provided with a portion 4 extending around over the upper edge of the body portion of the container which is bent inwardly at 5 so that it will extend into the material of the side wall of the container. The reinforcing metal band and the wall of the body portion of the container are bent as indicated in

Figure 7 to form a continuous external groove 6 and a continuous internal head-supporting rib 7. As indicated, the head 2 is so shaped that it has a portion resting on the internal rib 7. It also has a flange 8 which extends over the upper edge of the body portion of the container and downwardly into overlapping relationship to the metal reinforcing band 3. The structure so far described is substantially the same as the structure illustrated in my co-pending application. However, the retaining ring which I provide for retaining the head 2 in position on the body portion

is of different and novel construction.

The retaining ring 10 which I provide is a split retaining and clamping ring. It is adapted to be contracted around the upper end of the container and is provided with a portion adapted to cooperate with the head and a portion adapted to cooperate with the body portion of the container so that the head will be securely held in position. It is also provided with novel securing and locking means for holding it in contracted condition around the upper end of the container.

As illustrated in the drawing, the retaining ring has an inwardly projecting portion 11 on its lower edge. This continuous portion 11 is adapted to extend into the external continuous groove 6 formed by bending the body portion of the container and the metal band 3 as previously described. This portion 11 is so shaped that a continuous external groove 12 is formed which may receive a wire 13 which may be tightly contracted around this portion in order to aid in retaining the portion 11 in the groove 6. The upper edge of the retaining ring has a portion 14 formed thereon which is substantially vertically disposed but which has an inwardly extending curved lip 15 on its upper edge adapted to extend over and embrace the correspondingly curved portion at the upper end of the flange 8 of the head 2, as indicated best in Figure 7. Between these upper and lower portions 14 and 11 is an outwardly curved or convex rib portion 16. This portion 16 cooperates with a bead 8a formed on the lower edge of the flange 8 of head 2. It will be apparent that when the split retaining ring 10 is positioned on the container and is held in contracted condition, the head will be securely held in position on the container.

In order to secure and lock the retaining ring 10 in position on the container I provide the structure illustrated best in Figures 1 to 6 of the drawing. In Figure 1, I show the adjacent ends of the split ring. These ends are adapted to be disposed in overlapping relationship. They are provided with interfitting portions adapted to hold the ring in contracted condition. Thus, the end of the ring which will be on the inside is provided with a slot 17. This slot is formed in the portion 16 of the ring. The end of the ring which will be on the outside is provided with an inwardly projecting lug 18 which is also formed in the portion 16 of the ring. This lug 18 is formed by forcing the metal inwardly in such a manner that an elongated lug of substantially semicircular cross-section is produced and which projects beyond the inner surface of the portion 16 of the ring. This lug is of a length slightly less than that of slot 17. In forming this lug, a groove 18a is produced in the outer surface of the lug. The ends of this groove are closed by metal forced inwardly during the formation of the lug as at 18b. However, these end walls 18b are pierced as at 19 for receiving a locking pin or wire which will be referred to hereinafter.

In Figure 2 I show how the ends of the retaining ring are adapted to be disposed in overlapping relationship when the ring is contracted. The lug 18 on the outermost ring will project inwardly through the slot 17 of the innermost end of the ring. The lug is of almost the same length as the slot 17 and the ends of this lug will abut the ends of the slot and prevent relative longitudinal movement between the overlapping ends of the retaining ring. The ends of the slot 17 will contact with the inner flat surfaces of the end walls 18b of lug 18. The flat walls will,

therefore, prevent the ends of the slot from cutting into the metal of the lug 18. Thus, this structure will serve to maintain the retaining ring in contracted condition. The portion 16 of one end of the ring will closely embrace the corresponding portion of the other end of the ring as illustrated in Figure 2. Also, the opening 19 at each end of the lug 18 will communicate with the openings 20 at each end of the slot 17.

In order to prevent lateral or outward movement of the outer end of the ring so as to cause the lug 18 to be withdrawn from the cooperating slot 17, I provide a locking pin or wire 21. This locking pin or wire 21 is preferably initially of modified V-form. Its diverging ends are preferably spaced apart a distance substantially equal to the length of the lug 18. One end of the pin has a laterally extending portion 21a of substantial length. The other end also has a laterally extending portion 21b but which is comparatively short. In applying this pin to the overlapping ends of the ring, it is preferably positioned in the manner illustrated in Figure 3. That is, the end 21a is slipped through the hole 19 at one end of groove 18a and the end 21b is slipped into hole 19 at the other end of the groove. If the outer portion of this pin is hit with a hammer or other tool in the manner illustrated in Figure 3, the pin will be straightened out and the end 21b will be forced to the right (Figure 3) while the end 21a will remain substantially in the position indicated in Figure 3. Having the bent ends 21a and 21b facilitates positioning of the pin and makes it necessary to force one end only (end 21b) into position. The ends of the pin will extend through the openings 19 and 20 beneath the portion 16 of the inner end of the ring as indicated at 22 in Figures 4, 5 and 6. The pin will rest in the groove 18a formed in the outer surface of the lug 18. Thus, it will be apparent that this pin will serve to prevent the lug 18 from moving outwardly out of the slot 17.

It will be noted from the drawing that adjacent the ends of the groove 18a, the portion 16 of the ring is forced outwardly slightly as at 23 and adjacent the ends of the slot 17 the portion 16 is similarly bent outwardly as at 23a. This facilitates insertion of the pin 21. Also, it produces additional interfitting portions which enhance the locking action since they are so shaped that any force tending to pull the ends of the ring apart will also tend to force the lug 18 into slot 17, due to the cooperation of the portions 23 and 23a. It will be noted that the contact of the ends of the slot 17 with walls 18b is in front of the holes 19 (Figure 4).

In Figure 3 I show a slightly modified structure. The structure is exactly the same as that previously described with the exception that the lug 18c, corresponding to lug 18, is formed by slitting the portion 16 of the ring at two points spaced from each other and then forcing the metal inwardly. However, I prefer the structure illustrated in Figures 1 to 6.

It will be apparent that the means for securing and locking the ends of the retaining ring together is of such a nature that no portions will project outwardly beyond the portion 16 of the ring. Thus, there will be no projecting portions subject to injury or which will cause injury to a person handling the container. The locking pin 21 may be readily positioned when the retaining ring is placed on the container. It may be readily removed merely by using a screwdriver or other tool which may be forced underneath the pin in

the groove 18a and be used to bend it outwardly. This will quickly and easily withdraw the pin so that the retaining ring may be removed. The retaining ring is of such a structure that it may be used over and over again since the parts thereof will not be injured during its application to or removal from the container.

Various other objects and advantages will be apparent from the preceding description, the drawing and the following claims.

Having thus described my invention, what I claim is:

1. A split ring adapted to be applied to a container or similar article, said ring being adapted to have its ends in overlapping relationship, said ring having an outwardly curved continuous rib formed thereon, means for securing the ends of said ring together, said means comprising an inwardly projecting lug formed on the end of the ring disposed outermost, said lug being formed by forcing a portion of the metal of said rib inwardly to form a lug with a groove in the outer side thereof communicating at each end with the interior of said rib, a cooperating slot formed on the end of the ring disposed innermost and adapted to receive said lug, said slot being formed in said curved rib, means for maintaining the lug in position in the slot, said means comprising a pin resting in the outer groove formed in the lug and extending in opposite directions under the rib on the innermost end of the ring at points adjacent the ends of said slot.

2. A split ring adapted to be applied to a container or similar article, said ring being adapted to have its ends in overlapping relationship, means for securing the ends of said ring together, said means comprising an inwardly projecting lug formed on the end of the ring disposed outermost, said lug being formed by forcing a portion of the metal of the ring inwardly to form a lug with a groove in the outer side thereof and with the bottom of the groove disposed inwardly of the inner surface of said ring, a cooperating slot formed on the end of the ring disposed innermost and adapted to receive said lug, means for maintaining the lug in position in the slot, said means comprising a pin resting in the outer groove formed in the lug and extending in opposite directions under the innermost end of the ring at points adjacent the ends of the slot formed therein.

3. In combination, a container comprising a body portion, a head for closing the end of said body portion, a retaining ring for holding the head in position on said body portion, said retaining ring having a retaining portion adapted to cooperate with the head and a portion adapted to interfit with a portion of the container, said retaining ring being formed of metal and being split, said ring being adapted to have its ends in

overlapping relationship, means for securing the ends of said ring together to prevent relative longitudinal movement therebetween, said means comprising an inwardly projecting lug formed on the end of the ring disposed outermost and having a groove formed in the outer surface thereof and a cooperating slot formed in the end of the ring disposed innermost, said groove and said slot extending longitudinally of said ring, means for maintaining the lug in the slot, said means comprising a member extending longitudinally of the ring through the lug and into overlapping relationship to the ring at points adjacent the end of said slot.

4. A split ring adapted to be applied to a container or similar article, said ring being adapted to have its ends in overlapping relationship, means for securing the ends of said ring together, said means comprising an inwardly projecting lug formed on the end of the ring disposed outermost, said lug being formed by forcing a portion of the metal of the ring inwardly to form an elongated lug with a groove in the outer side thereof having a wall member at each end thereof, the bottom of the groove being disposed inwardly of the inner surface of said ring, a cooperating slot formed on the end of the ring disposed innermost and adapted to receive said lug, means for maintaining the lug in position in the slot, said means comprising a pin disposed in the outer groove formed in said lug and extending through openings formed in the wall members at the end of said groove in opposite directions under the innermost end of the ring at points adjacent the ends of the slot formed therein.

5. A split ring adapted to be applied to a container or similar article, said ring being adapted to have its ends in overlapping relationship, said ring having an outwardly curved continuous rib formed thereon, means for securing the ends of said ring together, said means comprising an inwardly projecting lug formed on the end of the ring disposed outermost, said lug being formed by forcing a portion of the metal of said rib inwardly to form an elongated lug with a groove in the outer side thereof having a wall member at each end thereof, the bottom of the groove being disposed inwardly of the inner surface of said rib, a cooperating slot formed on the end of the ring disposed innermost and adapted to receive said lug, said slot being formed in said curved rib, means for maintaining the lug in position in the slot, said means comprising a pin disposed in the outer groove formed in said lug and extending through openings formed in the wall members at the end of said groove in opposite directions under the innermost end of the ring at points adjacent the ends of the slot formed therein.

HANS A. EGGERSS. 60
